INVENTOR.

Louis Kreuzberger

United States Patent Office.

LOUIS KREUZBERGER, OF PHILADELPHIA, PENNSYLVANIA, ASSIGNOR
TO BRANER & CO., OF SAME PLACE.

Design No. 4,735, dated March 28, 1871.

DESIGN FOR BED-QUILTS.

The Schedule referred to in these Letters Patent and making part of the same.

I, LOUIS KREUZBERGER, of the city of Philadelphia and State of Pennsylvania, have invented and produced a new and original Design for Bed-Quilt, of which the following is a specification.

The nature of my design is fully represented in the accompanying photographic illustrations, to which reference is made.

My design consists of a series of blocks of rows of figures, *a*, which are four-square, with the exception of their having drop-stitches at the corners, triplicate rows of figures, *b* and *d*, which separate said blocks in one direction, and transverse triplicate rows of figures, *b'*, which separate the blocks in the other direction.

The figures *b* *d* *b'* are each alternately white and colored.

The lines of figures *b* and *d* are woven into the body of the cloth, which is white, and, consequently, show white spots between the stitches; but the colored figures *b'* are woven on the face of the cloth, and, consequently, show no white spots.

The squares *a* are also woven on the face of the cloth, and are alternately white and colored.

What I claim as my invention is—

The design for bed-quilt, as shown and described.

In testimony that the above is my invention I have hereunto set my hand and affixed my seal this 8th day of March, 1871.

LOUIS KREUZBERGER. [L. S.]
